AUTOMATIC TRAIN CONTROL SYSTEM

Filed Jan. 9, 1928

UNITED STATES PATENT OFFICE

EDWARD C. SASNETT, OF WASHINGTON, DISTRICT OF COLUMBIA, ASSIGNEE TO THE UNION SWITCH & SIGNAL COMPANY, OF SWISSVALE, PENNSYLVANIA, A CORPORATION OF PENNSYLVANIA

AUTOMATIC TRAIN CONTROL SYSTEM

Application filed January 9, 1928. Serial No. 245,377.

This invention relates to railway signalling and has particular reference to automatic train controlling systems of the code-continuous-indication type. The system herein shown is based on the system shown and claimed broadly in my copending application Serial No. 24,544, filed April 20, 1925.

Referring to the accompanying drawing, which shows diagrammatically a system embodying the invention: 10 designates a stretch of track divided by insulated joints 11 into blocks. The usual track relays 12 are connected across the rails at the entrance ends of the blocks, and located at each block station are a line relay 13, a track battery 14, a battery 15 of relatively high voltage (which may be the battery for operating the track signals, and a continuous current shunt-field motor 16. The apparatus at only one block station is shown in full, but of course this apparatus is duplicated at all the block stations.

As indicated, the motor armature is rigid with a shaft 20 on which is fixed, or to which is geared, an alternating current generator 18. The motor is connected to battery 15 through front contacts 24 of line relay 13, so that the motor is inactive when this relay is deenergized, which is the normal condition. Alternator 18 is connected by conductors 29 to conductors 32 through suitable non-inductive resistances 33. Formed on shaft 20, or suitably geared thereto, is a worm 21 which meshes with a worm wheel 30 fast on a shaft 31. Fixed on shaft 31 are three disks *a*, *b*, and *c*, formed with cam projections adapted respectively to operate the movable contacts of switches *x*, *y* and *z*, these contacts being connected to conductors 32. The stationary contacts of switch *x* are connected by conductors 34 and 35 to the track rails at the exit end of the block. The stationary contacts of switch *y* are connected to conductors 36, which are connected to back contacts 37 of the track relay, the movable contacts cooperating with these back contacts being connected by conductors 38 to the track rails at a suitable point in advance of the entrance end of the block. The stationary contacts

of switch *z* are connected by conductors 42 to the front contacts 43 of the track relay, the movable contacts cooperating with these front contacts being connected by conductors 40 to the track rails at the exit end of the block.

Under normal conditions, the motor 16, alternator 18 and the switch mechanism associated therewith are inactive, the circuit of the motor being open at front contacts 24 of line relay 13, and the track battery 14 is connected across the rails at the exit end of the block through back contacts 44 of the line relay and conductors 45 and 40. When a train enters the block, the circuit of line relay 13 is closed at back contacts 46 of the track relay connected to the block entered, and the line relay therefore picks up, disconnecting the track battery 14 and connecting battery 15 to motor 16. The motor accordingly rotates, driving alternator 18 and the cam discs *a*, *b* and *c*, the alternator applying an alternating potential to the movable contacts of switches *x*, *y* and *z*. Under safe traffic conditions the track relay 12 associated with the switches is energized, and therefore the stationary contacts of switches *x* and *z* only are connected to the track rails, the stationary contacts of switch *y* being connected to the rails directly through conductors 34 and 35, and the stationary contacts of switch *z* being connected to the rails through conductors 42, front contacts 43, and conductors 40. It will be observed that the cam projection of disk *a*, adapted to operate the movable contacts of switch *x*, extends through a relatively large angle, while the disc *c* is provided with two relatively short cam projections which are adapted to effect successively two short closures of switch *z* at each revolution of shaft 31. These short cam projections on disc *c* are angularly spaced from the long projection on disc *a*, so that there will occur at each revolution of shaft 31 two short closures of switch *z* followed by a relatively long closure of switch *x*.

When a train enters a block under caution conditions, the track relay immediately in advance being deenergized, the motor, alternator and switch mechanism will be set in

- operation as before, but the stationary contacts of switch α will be disconnected from the track rails at front contacts 43, while the stationary contacts of switches α and γ will be connected to the rails, the stationary contacts of switch γ being connected by conductors 36, back contacts 37 and conductors 38; and the stationary contacts of switch α being connected directly by conductors 34 and 35.
- It will be observed that the cam projection of disc b , adapted to operate the movable contacts of switch γ , is angularly displaced from the long cam projection of disc a . The switches α and γ therefore will operate under caution conditions to apply alternating voltage for a short period at the point where conductors 38 are connected to the rails and then for a relatively long period at the exit end of the block, at each revolution of shaft 31.
- From the foregoing it will be understood that a vehicle travelling on the track will receive under clear conditions two short impulses of alternating current followed by a long impulse, periodically, and that when a vehicle enters the block under caution conditions it will receive one short impulse followed by a long impulse, periodically, until it passes the point of connection of conductors 38, when it will receive only a succession of long impulses.
- At the left of the drawing a vehicle V is indicated by a pair of wheels and an axle. As is usual in inductive train control systems of the continuous indication type, the vehicle is provided with coils 50 carried adjacent the rails in advance of the first pair of wheels, so as to have threaded therethrough the alternating flux of the current flowing in the rails. These coils are connected to the winding of a relay 51, and if desired an amplifier A may be inserted between the coils and the relay.
- Relay 51 controls a code responsive mechanism which is adapted to respond to codes consisting of one or more short impulses followed by a long impulse. This mechanism comprises four small quick acting relays, 52, 53, 54 and 55, a slow acting relay 58, and two slow release relays 59 and 60.
- It will be understood from the foregoing that under clear traffic conditions, relay 51 will be energized intermittently by two short impulses followed by a long impulse, this code being recurrently or periodically received under clear conditions. Assuming all the magnets 52-55 to be deenergized, as shown, upon reception of the first short impulse relay 51 will pick up, closing the circuit of slow acting relay 58 and relay 52. The circuit of relay 58 is from battery B, conductor 62, front contact 63, conductor 64, relay 58, and conductors 65 and 66. The circuit of relay 52 is from battery B, conductor 62, front contact 63, conductor 67, back contact 68 of relay 58, conductor 56, relay 52, and conductors 69 and 66. The short impulses will not affect relay 58 since relay 58 is slow in picking up, but relay 52 will pick up and close a stick circuit for itself, which is from battery B, conductors 62 and 70, back contact 71 of slow acting relay 58, conductors 72 and 61, front contact 73 of relay 52, conductor 74, the winding of relay 52 and conductors 69 and 66. When relay 51 drops at the end of the short impulse, it closes the circuit of magnet 53, which is from battery B, conductor 62, back contact 75, conductor 76, back contact 76', conductor 76'', front contact 77 of relay 52, conductor 78, the winding of relay 53, and conductors 79 and 66. When relay 53 picks up it closes a stick circuit for itself, which is from battery B, conductors 62 and 70, back contact 71, conductor 72, conductor 81, front contact 82, conductor 83, the winding of relay 53, and conductors 79 and 66. When the next impulse is received, relay 54 picks up, its circuit being from battery B, conductor 62, front contact 63, conductor 67, back contact 68, conductors 56 and 57, front contacts 85 and 86 conductor 87, the winding of relay 54, and conductors 88 and 66. When relay 54 picks up it closes a stick circuit for itself, which is from battery B, conductors 62 and 70, back contact 71, conductors 72 and 80, conductor 89, front contact 90, conductor 91, the winding of relay 54 and conductors 88 and 66. When relay 51 drops at the end of the second short impulse, the circuit of relay 55 is closed, this circuit being from battery B, conductor 62, back contact 75, conductor 76, back contact 76', conductor 76'', front contacts 77, 92 and 93, conductor 94, the winding of relay 55, and conductors 95 and 66. When relay 55 picks up it closes a stick circuit for itself from battery B, conductors 62 and 70, back contact 71, conductors 72 and 80, conductor 96, front contact 97, conductor 98, and conductors 95 and 66. The next impulse received is the long impulse. This long impulse is of sufficient duration to cause slow acting relay 58 to pick up, which effects first the closure of its front contact 113 and then the opening of its back contact 71, the armature of this relay being provided with upper and lower spring contacts which cause the front contact to close in advance of the opening of the back contact. When the front contact closes it completes the circuit of slow release relays 59 and 60. The circuit of relay 59 is from battery B, conductors 62 and 70, front contact 113, conductor 114, front contacts 115, 116 and 117 of relays 52, 53 and 54, respectively, conductor 118, the winding of relay 59 and conductors 119, 120, and 66. The circuit of relay 60 is from battery B, conductors 62 and 70, front contact 113, conductor 114, front contacts 115, 116, 117 and 121, conductor 123, the winding of relay 60, and conductors 119, 120 and 66. It will be

noted that when the relay 58 picks up upon reception of the long impulse all the quick acting relays 52-55 will open their front contacts, since the stick circuits of all these relays are opened at back contact 71. Upon reception of the next code of two short and one long impulse, the relays 52-55 will successively pick up, another impulse will be sent through the slow release relays 59 and 60 and then the relays 52-55 will again drop. These operations will be repeated continually under clear traffic conditions, and the periodic impulses sent through relays 59 and 60 will be effective to cause these relays to continuously hold closed their front contacts. When both relays 59 and 60 are holding closed their front contacts, the circuit of a clear lamp 126 is closed, this circuit being obvious from the drawing.

When a vehicle enters a block under caution conditions, it will receive a code consisting of one short impulse followed by a long impulse until it passes the point of connection of conductors 38. This code will cause the relays 52, 53 and 54 to be successively energized and simultaneously deenergized, an impulse being sent through slow release relay 59 at the completion of each code, as will be clear from the foregoing. Impulses being no longer sent through slow release relay 60 this relay will open its front contacts and close its back contacts, opening the circuit of clear lamp 126 and closing the circuit of a caution lamp 127. When the vehicle passes the point of connection of conductors 38, it will receive a succession of long impulses, which will effect only the intermittent operation of slow acting relay 58 and quick acting relay 52, which of course will be ineffective to send an impulse through slow release relay 59. This latter relay will therefore open its front contacts and close its back contact, opening the circuit of caution lamp 127 and closing the circuit of a danger lamp 128.

The system of course can be combined with a speed controlled mechanism to impose a maximum speed when clear signal 126 is displayed; an intermediate speed, when caution signal 127 is displayed, and a low speed, when danger signal 128 is displayed. As such mechanism forms in itself no part of the present invention and is well known in the art, I deem it unnecessary to show such mechanism.

Having described my invention, I claim:

1. An automatic train control system comprising in combination, a track divided into blocks, means for intermittently connecting a source of alternating current across the track rails at the exit end of a block under clear traffic conditions and for intermittently connecting said source across the rails at the exit end of the block and also across the rails at an intermediate point of the block under caution conditions the connection of the source at said intermediate point occurring asynchronously with the connection at the exit end, and a vehicle having train control mechanism responsive to the current impulses flowing in the track rails. 70

2. An automatic train control system comprising in combination, a track divided into blocks, normally inactive means for intermittently connecting a source of alternating current across the rails at the exit end of a block when a vehicle enters that block under clear traffic conditions, and for intermittently connecting said source across the rails at the exit end of the block and also across the rails at an intermediate point of the block when a vehicle enters the block under caution conditions, the connections of the source at said intermediate point occurring asynchronously with the connections at the exit end, and a vehicle having train control mechanism responsive to the current impulses flowing in the track rails. 75

3. An automatic train control system comprising in combination, a track divided into insulated blocks, a track relay connected across the rails at the entrance end of each block, a track battery connected across the rails at the exit end of each block, normally inactive means for disconnecting the track battery from a block and for intermittently connecting a source of alternating current across the rails at the exit end of said block when a vehicle enters that block under clear traffic conditions and for intermittently connecting said source across the rails at the exit end of the block and also across the rails at an intermediate point of the block when a vehicle enters said block under caution conditions, the connections of the source at said intermediate point occurring asynchronously with the connections at the exit end, and a vehicle having controlling mechanism responsive to the current impulses flowing in the track rails. 80

4. An automatic train control system comprising in combination, a track divided into insulated blocks, means for producing a code of impulses in the track rails of a block under clear traffic conditions and a different code of impulses under caution traffic conditions, said clear code being produced by intermittently connecting a source of energy across the track rails at the exit end only of the block and said caution code being produced by connecting the same source of energy across the track rails at the exit end asynchronously with the connection of said source at an intermediate point of the block, and a vehicle having controlling mechanism responsive selectively to the two codes of impulses. 85

5. An automatic train control system comprising in combination, a track divided into insulated blocks, a track relay and a track

battery connected respectively across the rails at the entrance and exit ends of each block, means for producing a code of alternating current impulses in the track rails of a block under clear traffic conditions and a different code of alternating current impulses under caution traffic conditions, said clear code being produced by intermittently connecting a source of alternating current energy across the track rails at the exit end only of the block and said caution code being produced by connecting the same source of energy across the track rails at the exit end asynchronously with the connection of said source across the rails at an intermediate point in the block, and a vehicle having controlling mechanism responsive selectively to the two codes of impulses.

6. An automatic train controlling system comprising in combination, a track divided into insulated blocks, a track relay and a source of current connected across the track rails at the entrance and exit ends of each block respectively, normally inactive means for intermittently connecting a source of energy across the track rails of a block when a vehicle enters that block under clear traffic conditions to produce a periodic code of impulses in the rails, the code consisting of a relatively long impulse and a plurality of short impulses, and a vehicle controlling means responsive to said code, said means comprising a relay on the vehicle responsive to the impulses, a slow acting relay the circuit of which is closed when said vehicle relay is energized, a series of quick acting relays consecutively energized as said vehicle relay is energized and deenergized, stick circuits respectively for said quick acting relays, all of said stick circuits including a back contact of said slow acting relay, and a vehicle controlling circuit including in series front contacts of said quick acting relays and a front contact of said slow acting relay.

7. An automatic train control system comprising in combination with means to produce in the track rails a recurrent code of impulses consisting of a relatively long impulse and at least one short impulse, a vehicle on the track having a relay responsive to the impulses, a slow acting relay the circuit of which is closed when said vehicle relay is energized, and a plurality of quick acting relays consecutively energized as said vehicle relay is energized and deenergized, stick circuits respectively for said quick acting relays, all of said stick circuits including a back contact of said slow acting relay, and a vehicle controlling circuit including in series front contacts of said quick acting relays and a front contact of said slow acting relay.

8. An automatic train control system comprising in combination a track divided into insulated blocks, a track relay connected

across the rails at the entrance end of each block, a track battery connected across the rails at the exit end of each block, a normally inactive motor and an alternator and switch mechanism driven by the motor associated with each track relay, means actuated when a vehicle enters a block to disconnect the track battery from that block and to set in operation the motor associated therewith, said alternator being connected across the track rails at the exit end of said block through the switch mechanism associated therewith and said switch mechanism operating to connect the alternator intermittently to produce in the rails predetermined codes of impulses according to traffic condition, and a vehicle having controlling means selectively responsive to the codes of impulses.

9. An automatic train control system comprising in combination, a track divided into insulated blocks, a track relay and a track battery connected across the rails respectively at the entrance and exit ends of each block, means for producing a code of impulses in the track rails of a block under clear traffic conditions and a different code of impulses under caution traffic conditions, said clear code being produced by intermittently connecting a source of energy across the track rails at the exit end only of the block and said caution code being produced by connecting the same source of energy across the track rails at the exit end asynchronously with the connections of said source across the rails at an intermediate point in the block, and a vehicle having controlling mechanism responsive selectively to the two codes of impulses.

10. An automatic train control system comprising in combination, a track divided into insulated blocks, a track relay connected across the rails at the entrance end of each block, a track battery connected across the rails at the exit end of each block, a normally inactive motor and an alternator driven thereby associated with each track relay, means actuated when a vehicle enters a block to disconnect the track battery from that block and to set in operation the motor associated therewith, and traffic controlled means for connecting the alternator driven by said motor across the track rails at the exit end of said block.

11. An automatic train control system comprising in combination, a track divided into insulated blocks, a track relay connected across the rails at one end of each block, a source of current connected across the rails at the other end of each block, a normally inactive motor and an alternator driven thereby associated with each track relay, means actuated when a vehicle enters a block to disconnect the source from that block and to set in operation the motor associated there-

with, and traffic controlled means for connecting the alternator driven by said motor across the rails of said block.

12. An automatic train control system comprising in combination, a track divided into insulated blocks, a track relay connected across the rails at one end of each block, a source of current connected across the rails at the other end of each block, a normally inactive motor and an alternator and switch mechanism driven by the motor associated with each track relay, means controlled by each track relay and actuated when a vehicle enters the corresponding block to set in operation the motor associated therewith, and means for connecting each alternator with the rails of the corresponding block through the associated switch mechanism to produce in the rails a code of periodically varied alternating current.

13. In combination, a stretch of railway track, a source of direct current, an alternating current generator operated by current from said source, means for supplying current from said generator to the rails of said stretch, and means for at times periodically interrupting such alternating current at different frequencies depending upon traffic conditions.

14. In combination, a stretch of railway track, a source of direct current, apparatus receiving energy from said source for generating uninterrupted alternating current, a contact arranged to operate periodically at a predetermined frequency, and means including said contact for supplying current from said apparatus to the rails of said stretch.

15. In combination, a stretch of railway track, a source of direct current, apparatus receiving energy from said source for generating uninterrupted alternating current, a plurality of contacts arranged to operate periodically at different frequencies, and means for supplying alternating current from said apparatus to the rails of said stretch over a selected one of said contacts depending upon traffic conditions.

16. In combination, a stretch of railway track, a source of direct current, a motor operated by current from said source, an alternating current generator driven by said motor, a contact operated intermittently by said motor, and means including said contact for supplying alternating current from said generator to the rails of said stretch.

17. In combination, a stretch of railway track, a source of direct current, a motor operated by current from said source, an alternating current generator driven by said motor, a plurality of contacts, means driven by said motor for operating said contacts at different frequencies, and means for supplying current from said generator to the rails of said stretch over a selected one of said contacts.

18. In combination, a stretch of railway track, a source of direct current, a relay responsive to traffic conditions in said stretch, a direct current motor, means controlled by said relay for connecting said motor with said source when said stretch is occupied by a train, an alternating current generator driven by said motor, a contact, means driven by said motor for periodically operating said contact, and means including said contact for supplying current from said generator to said stretch.

In testimony whereof I hereunto affix my signature.

EDWARD C. SASNETT.
